UNITED STATES PATENT OFFICE.

OMERIL TARDIF, OF PLESSISVILLE, QUEBEC, CANADA, ASSIGNOR TO LA FONDERIE DE PLESSISVILLE, OF PLESSISVILLE, QUEBEC, CANADA.

SAWING MACHINE.

Application filed December 27, 1920. Serial No. 433,331.

To all whom it may concern:

Be it known that I, OMERIL TARDIF, a British subject, engineer, residing at Plessisville, in the Province of Quebec, in the Dominion of Canada, have invented certain new and useful Improvements in Sawing Machines; and I do hereby declare that the following is a full, clear, and exact description of the same.

10 The present invention relates to improvements in sawing machines of the twin type, and the main object is to provide a machine of this character in which the saws can be drawn very close to one another owing to 15 the particular means of securing them on the shafts.

Another object is to provide means for carrying the logs to the saws, said means being such that they can operate even when 20 the saws are drawn close together.

For a complete understanding of the invention, reference may be had to the accompanying description and drawings, in which:

25 Figure 1 is a side elevation of one form of machine according to the invention.

Figure 2 is a top view of the machine.

Figure 3 is an enlarged side elevation of one of the chain driving wheels.

30 Figure 4 is a vertical sectional view on line A—A of Figure 3.

Figure 5 is an enlarged vertical sectional view through the saw support mounted on the driving shaft.

35 Figure 6 is an enlarged side elevation of a portion of the driving chain.

Figure 7 is a top view of a portion of Figure 6.

Figure 8 is a vertical section view on line 40 B—B of Figure 6.

Like numerals of reference indicate corresponding parts in each figure.

Referring to the drawings, 1 is the supporting frame, and 2 are the supports for 45 the shafts 3 carrying the saws 4. Suitable bearings 5 are provided on said supports in which the shafts 3 are journaled, said shafts being preferably slidable in said bearings and being operated by the arms 6 which 50 are pivotally secured at 7 to the supports 2. The shafts 3 have a loose connection with the central portions of said arms 6, the latter being pivotally connected at their free ends to links 8 which are eccentrically con-

nected to a wheel 9. Thus when said wheel 55 9 is operated, the shafts 3 are drawn closer to one another, or pulled apart, according to the thickness it is desired to cut the logs. On each end of said frame 1, are mounted the chain carrying or driving wheels 10, 60 said wheels being journaled in the bearings 11 on the supports 12, and intermediate of one of said wheels 10 and the shaft supports 2 is mounted the guideway 13 in which the chain 14 slides. Adjacent said guideway 13 are provided suitable devices 16 for feeding the logs 15 between the rollers 17, which are located on each side of the guideway and which serve to center the logs with relation to the guideway and to hold them 70 in position until engaged by the hereinafter-described pusher heads 27 on the chain. The feeding devices 16 form no part of the invention, and, hence, need no special description.

75 The shaft of one of the driving wheels 10 carries a gear 18 which is connected to be driven from a suitable source of power, and the pulleys 19 mounted on the saw shafts 3 and the log-feeding devices 16 are also 80 driven from the same or some other source or sources of power.

The driving wheels 10 are preferably octagonal in shape; and in the opposite side faces of each of them are provided four depressions or cavities 18*, each pair of mating cavities being connected by an opening 19* which extends right through the wheel. The inner edge 20 of the opening or passage 19*, or edge nearest the center of said wheel, 90 is preferably V-shaped. In alignment with said edge 20, is provided in the outer edge 21 a vertical slot 22 which opens through the adjacent flat edge face 23 of the octagon wheel. Each of said slots 22 is adapted to 95 receive one of the depending links 24 of the chain 14. The links of the chain 14 frequently carry wood scrapings which would clog slots 22 of the wheel 10, if openings 19* were not provided. By means of these 100 openings, the scrapings will fall therethrough and the sharp edge 20 will divert them on each side of the wheel 10.

The chain 14 consists of a plurality of links 24 each of which has a depending 105 member 25, these links being pivotally connected by the straight links 26. At suitable intervals the chain is provided with vertical

heads 27 which preferably have sharp, toothed side edges 28. These heads 27 are adapted to engage the rear ends of the logs 15, and carry them through the saws 4. The heads 27 are thin enough to pass in between the saws 4, and the links 24 engage in the guideway 13, which stiffens the chain 14 when the logs are carried to the saws and provides a better operation of the carrier.

10 Each shaft 3, adjacent its inner end, is provided with a flange 29, leaving a projecting portion 30 which is preferably threaded. On the threaded portion is adapted to engage a threaded disk or nut 31, which abuts against said flange 29, said disk having a circumferential depression 32 on one face thereof, and 33 are holes which extend right through said disk, in said depression 32. In said depression 32 is secured the circular saw 4, and 34 is a ring adapted to engage over said saw 4, and close said depression 32, in order to form a flat or flush surface 35. The ring 34 is provided with a plurality of holes 36 having an expanding portion 25 to receive the heads of the bolts 37 which project through said ring, saw and disk 31, and are secured by means of the nuts 38. Thus, it will readily be seen that the saws 4 can be closed up to cut a very thin board, owing to the flush surfaces 35, and the thin

heads 27, which carry the logs to the saws. What I claim as my invention is:

1. A feeding mechanism for saws, comprising an endless conveyer belt leading to the saw and composed of pivotally-connected links having projections on their inner faces, and wheels around which the belt passes at opposite ends; said wheels having peripheral slots in which the projections on said links are adapted to engage, and 40 also having passages formed transversely through them and into which the inner ends of the slots open, said passages having their inner edges beveled so as to discharge at opposite sides of the wheels any sawdust or the 45 like which may enter the slots and thereby prevent said slots from becoming clogged.

2. A feeding mechanism for saws, as claimed in claim 1, in which certain of the projections have heads which extend outwardly beyond the outer faces of the links 50 for engagement with the material to be sawed.

Signed at Plessisville, Quebec, Canada,
this 25th day of November, 1920.

OMERIL TARDIF.
